UNITED STATES PATENT OFFICE

ALAN D. DAUCH, OF PITTSBURGH, PENNSYLVANIA, ASSIGNOR TO GEORGE J. HAGAN COMPANY, OF PITTSBURGH, PENNSYLVANIA, A CORPORATION OF PENNSYLVANIA

ROTARY-HEARTH FURNACE

Application filed March 20, 1926. Serial No. 96,192.

My invention relates to industrial heating furnaces, more particularly to apparatus for manipulating the work or articles to be heated.

5 It is among the objects of my invention to provide an improved type of industrial heating furnace which shall embody means for mechanically discharging the work or articles, that have been heated, from the furnace chamber.

10 Another object of my invention is to provide mechanical operating means for industrial heating furnaces which shall greatly facilitate the handling of the heated articles in discharging the same so as to maintain the operating temperature of the furnace, and where the heated articles are to be hardened, to keep them at suitable quenching heats.

15 Another object of my invention is to provide mechanical operating means of the above designated character which shall be adapted for discharging work from furnaces in a manner to effect its proper distribution for subjecting it to a quenching bath.

20 Industrial heating furnaces of the type embodying a movable hearth, as for example rotary hearth furnaces, are provided with passages or openings for loading the articles to be heated on the furnace hearth, or in suitable trays or removable supports which are placed on the hearth member and for unloading the work or work-carrying members by lifting or removing the trays or supports from the hearth through the discharge openings.

25 The charging passages are at the cold side of the furnace chamber and the discharge passage or passages at the hot end of the furnace so that it is important to handle the heated articles in a minimum of time in discharging them from the furnace to prevent loss of heat in the furnace and also to prevent as much as possible a drop in the temperature of the heated articles when they are to be subjected to a quenching operation.

30 It has been the customary practice to charge the furnace by placing the articles to be heated in suitable trays which are inserted through charging passages into the furnace chamber and placed upon the movable hearth.

35 The trays were subsequently removed by one

or more operators by manually lifting them off the hearth and withdrawing them through the discharge passage.

In accordance with my present invention I employ a plurality of work-carrying trays which are securely fixed to the hearth so as to be a permanent part thereof, the trays being mounted in such a manner that they may be readily removed for renewal or repairs. The trays being fixed to the hearth are not required to be heated other than to the extent to which they are cooled by a cold charge of material whereas by the method of removing the trays from the furnace chamber the tray in addition to its charge had to be heated to the operating temperature of the furnace, thus materially increasing the load of the furnace.

I further provide a mechanical operating mechanism for discharging the contents of the trays at the discharge passage of the furnace to eliminate the extensive manipulation of the work by operators which left the discharge passage open for sufficient lengths of time to effect a material drop in the temperature of the furnace. I further provide means cooperating with the mechanical discharging apparatus for operating the cover member or closure of the discharge passage to open the passage when the mechanism functions to unload the charge from the trays and to automatically close the same when the discharge mechanism assumes its inoperative position.

In the accompanying drawings constituting a part hereof and in which like reference characters designate like parts, Fig. 1 is a view partially in section and partially in elevation of a rotary hearth furnace embodying the principles of my invention; and Fig. 2 is a cross-sectional view thereof illustrating the relative position of the work-carrying trays which are supported on the hearth.

Referring to Fig. 1 of the drawings, the structure therein illustrated comprises a pedestal support 1 provided with a clamping ring 2 to which is secured a bearing support 3 having a central opening 4 and a countersunk portion 5 the latter being adapted to receive the annular race of a ball bearing 6. A rotatable support 7 having a central hub

100

portion 8 provided with a depending flange 9 is mounted on the bearing member 6, the flanges 5 and 9 of the bearing support and rotating member 7 cooperating to enclose the bearing member 6. A vertical spindle or drive shaft 10 is secured to the rotatable support 7 to adapt the latter to rotate therewith and is journaled in the center column 11 of the furnace member and provided with a suitable drive connection comprising a pair of bevel gears 12 and 13. The gear 13 is mounted on a shaft 14 carrying a worm wheel contained in the gear case 15, the worm wheel interacting with a worm shaft 16 connected by the coupling 17 to drive motor 18, adapted for intermittent rotation.

A hearth 20 is secured to the rotatable support 7 by suitable angle bars 21 and a plurality of segment-shaped trays 22 having pedestal supports 23 are hinged at 24 to mounting brackets anchored in the hearth portion 20. The trays 22 are closed at their inner ends and open at the ends extending to the outer extremity of the hearth.

The furnace wall 25 is constructed of suitable refractory and heat-insulating material and a roof 26 of similar material forms a chamber 27 with the outer walls 25 and the center column 11.

The furnace wall 25 is provided with openings or passages 30 and 31 for respectively charging and discharging the articles to be heated into and from the segment shaped trays 22 of the hearth. The passages 30 and 31 are separated by a partition wall not shown which extends from the outer wall 25 to the center column 11 of the furnace for the purpose of preventing a cooling of the furnace chamber in the region of the discharge passage 31 which is the hot zone of the furnace. Suitable heating elements 32 and 33 are disposed around the inner and outer walls of the wall portion 25 and center column 11, respectively, these elements being energized from a suitable source of electrical energy.

The discharge passage 31 is provided with a chute 35, the upper extremity of which is in alignment with the tray members 22 and a door 36 is connected to angle bars 37 secured to the sides of the passage 35 to prevent the infiltration of cold air into the heating chamber. The door 36 is provided with a bracket 38 which is connected by a cable 39 extending over a pulley 40 to a lever 41.

The trays 22 are adapted to be raised above their hinged supports 24 to discharge their contents into the chute 35 by means of a gripping member or hook 43, that is secured to a movable ram 44 and adapted to extend underneath the trays 22 to engage the latter when the ram 44 is actuated. The ram is disposed for longitudinal movement in a metal housing 45 which extends through the roof 26 of the furnace and is fastened to the struc-

tural frame work 46 carrying the driving mechanism previously described.

A vertical extension 47 is connected to the cross-member 46 and a bearing bracket 48 is mounted on the cross member to rotatably journal a screw mechanism comprising a screw shaft 49 having a bevel gear 50 secured at its lower extremity which is in cooperative engagement with a gear wheel 51 mounted on the shaft of a motor 52. The extended end of the screw shaft 49 is similarly journaled in an angle bracket 53 secured to the top or crest of the vertical extension 47. A guide rod 54 is clamped at its respective ends to the brackets 48 and 53 and a nut member 55 having a threaded opening interacting with the threads of the screw shaft 49 is provided with an opening for receiving the guide rod 54 to guide the nut 55 in its axial movement along the screw shaft 49 to the position indicated by the dotted lines. The nut member 55 connects to the ram 44 which extends through an opening provided in the bracket 48 and through the casing 45.

In operation, the discharging mechanism comprising the hook 43 and the screw actuated ram functions to lift the trays in the manner shown in the dotted line construction against the roof of the furnace which is provided with a stop block 57 with which the trays are engaged with a certain amount of impact to cause the articles carried by the tray to be loosened and passed into the chute 35. When the gripping member or hook 43 assumes the position in which the tray 22 is fully tilted the nut member 55 will have traversed the tripping lever 41 which extends directly in its path and by engaging the same the door 36 is raised on its hinge to open the passage through which the material is discharged into a quenching bath or onto a suitable conveyor.

The segment shape of the tray members 22 effects a spreading or scattering of the articles carried on the tray at the instant they are discharged therefrom, which is desirable to properly distribute the material before submitting it to the quenching fluid and to enhance this spreading of the articles the tray may be provided with a flared bottom or otherwise shaped to carry out this function.

When the contents of the tray have been discharged through the chute 35 the motor 52 is operated in a reverse direction of rotation to cause the gripping member 43 to assume its normal or lowered position as shown in Fig. 1, and the door 36 will close by gravity when the trip lever 41 is released. It is evident that by the utilization of hinged trays which are permanently mounted on the hearth of the furnace and the mechanical tilting mechanism the articles or work may be readily discharged through the discharge passage 31 in a minimum of time and without manual labor and that the tray-tilting mechanism will be

adapted to function in its tilting operation for each successive tray as it is brought in alignment with the discharge passage by intermittent rotation of the rotatable support on which the hearth is mounted.

It is obvious that the tray-lifting mechanism may be disposed underneath the hearth and arranged to function in pushing the tray upward about its hinged support or that the tray may be hinged at its other end and discharge its contents to a chute adapted to convey it from the center of the furnace.

15 Although I have described one of the embodiments of my invention, it will be obvious to those skilled in the art that various modifications may be made in the details of construction and in the design and arrangement of the several cooperating parts without departing from the principles herein set forth.

20 I claim:

20 1. In an industrial heating furnace the
combination with a movable hearth of a plu-
rality of work carrying members supported
thereon, said furnace being provided with
25 passages communicating with the furnace
chamber, and means independent of the
movement of said hearth for actuating said
carrying members to discharge the work
through one of said passages.

30 2. In an industrial heating furnace the combination with a movable hearth of a plurality of work carrying members supported thereon, said furnace being provided with passages communicating with the furnace chamber, and actuating means independent of the movement of the hearth for tilting said carrying members to discharge the work through one of said passages.

35

40   3. In an industrial heating furnace the combination with a movable hearth of a plurality of work carrying members supported thereon, said furnace being provided with passages communicating with the furnace chamber, a drive mechanism for imparting intermittent movement to said hearth, and means for actuating said carrying members to discharge the work through one of said passages when the movement of said hearth is interrupted.

50 4. In an industrial heating furnace the combination with a movable hearth of a plurality of work carrying members supported thereon, said furnace being provided with closed passages communicating with the furnace chamber, means for actuating said carrying members to discharge the work through one of said passages, and means associated with said actuating means for opening said discharge passage.

5. In an industrial heating furnace the combination with a movable hearth of a plurality of work carrying members supported thereon, said furnace being provided with closed passages communicating with the furnace chamber, means independent of the

movement of the hearth for actuating said carrying members to discharge the work through one of said passages, and means for automatically opening said discharge passage simultaneously with the discharging of the work therethrough. 70

6. In an industrial heating furnace the combination with a rotatable hearth of a plurality of work carrying members supported thereon, said furnace being provided with passages communicating with the furnace chamber, and actuating means independent of the movement of the hearth for discharging the work through one of said passages when said work carrying members are in co-operative alignment therewith. 75 80

7. In an industrial heating furnace the combination with a rotatable hearth of a plurality of work carrying members supported thereon, said furnace being provided with passages communicating with the furnace chamber, a drive mechanism for imparting intermittent rotative movement to said hearth and means for discharging the work from said carrying member through one of said passages when the movement of the hearth is interrupted. 85 90

8. In an industrial heating furnace the combination with a rotatable hearth of a plurality of segment shaped trays for carrying articles to be heated secured by hinges at their large end to the outer portion of said hearth and means for moving said trays angularly about their hinge supports to discharge their contents. 100

9. An industrial heating furnace comprising a furnace chamber, a rotatable support journaled for rotation about a vertical axis in said chamber, an annular hearth carried by said support, a plurality of segment shaped trays pivotally connected at one of their ends to said hearth, means for providing uniform heat circulation around said trays, means for actuating said support to provide intermittent rotative movement to said hearth and trays, and means for raising said trays on their hinge supports to discharge their contents.

11. A furnace provided with a discharge opening, a movable hearth within the furnace, material carrying pans upon said hearth, means for moving the hearth through the furnace, means for stopping the hearth as each pan registers with the discharge opening and means for dumping each pan as it registers with the discharge opening.

12. A furnace provided with a discharge opening, a rotary hearth within the furnace, material carrying pans upon said hearth, means for rotating the hearth within the furnace, means for stopping the hearth as each pan registers with the discharge opening and means for dumping each pan as it registers with the discharge opening.

13. A furnace provided with a charging opening and a discharge opening, a movable hearth within the furnace, material carrying pans upon said hearth, means for moving the hearth, means for stopping the hearth as one pan registers with the charging opening and another pan registers with the discharge opening, and means for dumping each pan as it registers with the discharge opening.

14. In an industrial heating furnace the combination with a movable hearth of a plurality of work carrying members supported thereon, said furnace being provided with passages communicating with the furnace chamber, and means independent of the movement of the hearth for actuating said carrying members and for freeing the work from its support to discharge the same through one of said passages.

15. In an industrial heating furnace the combination with a movable hearth of a plurality of work carrying members supported thereon, said furnace being provided with passages communicating with the furnace chamber, means independent of the movement of said hearth for actuating said carrying members and means for freeing the work from its support to discharge the same through one of said passages.

16. In an industrial heating furnace the combination with a movable hearth of a plurality of work carrying members supported thereon, said furnace being provided with passages communicating with the furnace chamber, and means independent of the movement of said hearth for successively actuating said carrying members to discharge the work through one of said passages.

17. In an industrial heating furnace the combination with a movable hearth of a plurality of work carrying members supported thereon, said furnace being provided with passages communicating with the furnace chamber, and means independent of the movement of said hearth and operatively disposed in alinement with one of said passages for successively actuating said carrying mem-

bers to discharge the work through said passage.

18. In a furnace, the combination with a movable hearth of means for jarring said hearth.

In testimony whereof I sign my name.

ALAN D. DAUCH.
